UNITED STATES PATENT OFFICE.

RICHARD MOSES, OF DECATUR, TEXAS.

KEYLESS PADLOCK.

1,165,892.

Specification of Letters Patent. Patented Dec. 28, 1915.

Application filed July 9, 1915. Serial No. 38,928.

To all whom it may concern:

Be it known that I, RICHARD MOSES, a citizen of the United States, residing at Decatur, in the county of Wise and State of Texas, have invented certain new and useful improvements in Keyless Padlocks; and I do hereby declare the following to be a full, clear, and exact description of the invention, such as will enable others skilled in the art 10 to which it appertains to make and use the same, reference being had to the accompanying drawings, and to the letters and figures of reference marked thereon, which form a part of this specification.

15 This invention relates to new and useful improvements in keyless padlocks and comprises a simple and efficient device of this nature having various details of construction, combinations and arrangements of 20 parts which will be hereinafter fully described, shown in the accompanying drawings and then specifically defined in the appended claims.

25 My invention is illustrated in the accompanying drawings, in which:

Figure 1 is a side elevation of a lock made in accordance with my invention, a part being shown in section. Fig. 2 is a sectional view on line 2—2 of Fig. 1, Fig. 3 is a front 30 elevation of the dial, and Fig. 4 is a detail view of the spring lock bar.

Reference now being had to the details of the drawings by letter, A designates the body portion of a padlock having a way B 35 in one side in which the tongue D is adapted to move. A spring F is mounted within said way and adapted to bear against the end of the tongue to hold the same closed. A graduated cylinder H, with numerals 40 upon the outer face thereof, is mounted in the body portion of the padlock and the inner portion of the cylinder is provided with a recess or slot K.

N designates a push button with its inner end N' contracted and adapted to engage the slot or recess K and is connected to a resilient locking member O, the end of which is adapted to engage a recess Q in the tongue to hold the latter locked. A second 55 spring R is fastened to the push button and serves to normally return the latter after having been pressed down to allow its inner end to engage the slot in the cylindrical member and to unlock the tongue.

60 The operation of my invention will be

readily understood and is as follows:—The tongue being locked may be opened by turning the cylinder with the dial thereon until the recess or slot comes in alinement with the contracted end N' of the push button, 60 after which the operator, by pressing in upon the end of the push button, may cause the contracted end to engage said recess, the locking member O yielding sufficiently to cause its locking end to be withdrawn from 65 the notch in the shank portion of the tongue, at the same time putting the spring R under tension. As the tongue is closed and pressure released from the push button, the tongue will automatically lock. 70

What I claim to be new is:—

1. A keyless padlock provided with a body portion having a spring-pressed tongue pivotally mounted thereon and having a notch near its free end, the top of the body portion having an aperture, a rotatable tumbler with a notch in the circumference thereof, a transversely mounted resilient locking member pivoted at one end within said body portion and its free end adapted to 80 engage the notch in the tongue, a spring-pressed push button extending through an aperture in the top of said body portion and its lower end adapted to engage the notch in the tumbler and in alinement therewith, a 85 projection upon said push button bearing against the locking member at substantially its central portion and designed to cause said locking member to yield sufficiently when the push button is depressed to cause 90 the clear end of said locking member to free the notch in the tongue. 75

2. A keyless padlock provided with a body portion having a spring-pressed tongue pivotally mounted thereon and having a notch near its free end, the top of the body portion having an aperture, a rotatable tumbler with a notch in the circumference thereof, a transversely mounted resilient locking member pivoted at one end within said body portion and its free end adapted to engage the notch in the tongue, said locking member having a recess in one edge thereof adjacent to its longitudinal center, a spring-pressed push button having its upper end 100 contracted and terminating in a shoulder, said contracted end passing through an aperture in the top of the body portion and a shoulder adapted to contact with the top to limit the movement of the push button in 110

one direction, the inner end of the push button designed to engage said slot when in alinement therewith, the push button movable in said recess of the locking member,
5 and a pin projecting from the push button adapted to engage the upper surface of the locking member.

In testimony whereof I hereunto affix my signature in presence of two witnesses.

RICHARD MOSES.
